UNITED STATES PATENT OFFICE.

MICHAEL W. HANLEY, OF CHICAGO, ILLINOIS.

SEPARATOR FOR STEAM-GENERATORS.

SPECIFICATION forming part of Letters Patent No. 355,166, dated December 28, 1886.

Application filed April 25, 1884. Serial No. 129,296. (No model.)

To all whom it may concern:

Be it known that I, MICHAEL W. HANLEY, a citizen of the United States, residing at Chicago, in the county of Cook and State of Illinois, have invented certain new and useful 5 Improvements in Separators for Steam-Generators, which are fully set forth in the following specification, reference being had to the accompanying drawings, in which—

10 Figure 1 represents a longitudinal vertical section of a steam-generator embodying my improvements; and Fig. 2, a cross section of the same, taken on the line *x x* in Fig. 1.

15 My invention relates to separators for steam-generators, its object being to provide means for producing anhydrous steam, or, in other words, to prevent the water which may be mingled with the steam from passing through the boiler into the steam-pipe; and to this end 20 my invention consists in certain novel features, which I will now proceed to describe, and will then particularly point out in the claims.

25 In the drawings I have shown my separator applied to a steam-generator, in which A represents the furnace provided with a fire-chamber, B, at one end, having the usual grate-bars, *b*, and fire-wall *b'* and a cap, *b*², preferably constructed of, or at least lined with light-colored fire-brick. C represents the boiler set 30 upon the furnace in the usual manner, this latter being provided with barrier-walls D underneath the same, forming a series of combustion-chambers. The boiler-flues E, preferably concavo-convex, as shown, lead from 35 the rear end of the furnace to the draft-flue F, which latter communicates with the chimney G. The draft-flue is provided with a damper, H, connected by means of a rod, *h*², to a crank-arm, *i*, on a rock-shaft, I, the other end of the 40 rock-shaft being provided with a similar crank-arm, *i'*, to which the rod J for operating the damper or draft-regulator is connected.

45 The parts just described constitute my preferred form of steam-generator, although, of course, any approved apparatus for the purpose may be substituted therefor, and I do not limit myself to this particular construction.

My improved separator is constructed as follows:

L represents a steam-dome mounted upon 50 the boiler, on the top thereof, and *c* a steam-pipe extending upward through the bottom of said dome into the same and terminating within it a short distance below the top thereof.

M represents a cap or casing arranged within 55 the steam-dome over the open upper end of the steam-pipe *c*, the said casing having a closed upper end and closed lower end, and being somewhat larger than the steam-pipe, the upper end of which it incloses and surrounds without closing the same, as clearly shown in the several figures of the drawings. In operation it will be seen that the steam passing up through the steam-pipe *c* is thrown down again by the cap or casing between it 60 and the pipe, so that the steam is forced down onto the boiler surface or bottom of the dome, from whence it arises to the upper part of the dome and is taken off for use by means of a supply-pipe, N, in a dry condition. The re- 65 sult of this operation upon the steam is to deprive it of any spray or water which it may have carried from the boiler, the water being arrested at the bottom of the steam-dome, and the steam being delivered in a nearly dry or 70 anhydrous condition.

75 The cap M is supported within the steam-dome by means of lugs or flanges *m*, or any other suitable supporting-arms. A faucet, *l*, is applied to the lower edge of the steam-dome, 80 as shown in Fig. 2 of the drawings, so that the water and condensed steam accumulating in the dome may be drawn off whenever desired.

Having thus described my invention, what I claim as new, and desire to secure by Letters Patent, is—

1. In a separator for steam-generators, the combination, with a steam-dome and a steam-pipe passing upward through the bottom of said dome, of a cap or casing closed at the top 90 and open at the bottom and covering the open upper end of the steam-pipe, substantially as specified.

2. In a separator for steam-generators, the combination, with a steam-dome closed at the 95 bottom and a steam-pipe passing upwardly through said closed bottom and terminating within the dome, of a cap or casing having a

closed upper end and open lower end, the said dome, pipe, and casing being arranged substantially as shown and described, and for the purposes specified.

5 3. The combination, with the boiler G and steam-dome L, closed at the bottom, of the pipe c, extending from the boiler upward into the steam-dome, and the cap M, arranged within

the dome above the end of the pipe c, and extending downward around the same toward the bottom of the dome, substantially as and for the purposes specified.

MICHAEL W. HANLEY.
